UNITED STATES PATENT OFFICE.

WALTER E. VERKLER, OF CHICAGO, ILLINOIS.

MEANS FOR DRIVING MULTIGRAPH APPARATUS.

Application filed October 10, 1921. Serial No. 506,841.

To all whom it may concern:

Be it known that I, WALTER E. VERKLER, a citizen of the United States, and a resident of the city of Chicago, county of Cook, and State of Illinois, have invented certain new and useful Improvements in Means for Driving Multigraph Apparatus, of which the following is a specification.

My invention relates to improvements in means for driving multigraph apparatus by the application of electric energy, and has for its principal object the provision of an improved construction of this character which will be highly efficient in use.

16 Other objects will appear hereinafter.

The invention consists in the combinations and arrangements of parts hereinafter described and claimed.

The invention will be best understood by reference to the accompanying drawings forming a part of this specification, and in which,

Fig. 1 is a view of the discharge end of a multigraph apparatus showing my improved driving means mounted thereon,

Fig. 2 is an end view of the same,

Fig. 3 is a view of the opposite end of the same, and

Fig. 4 is a detail sectional view of the 20 signature shifting mechanism embodied in the invention.

Heretofore, the means for driving a multigraph apparatus by the application of electric energy was through the medium of a pinion meshing with the platen roller pinion, which in turn meshes with the printing drum gear teeth. In practical use this means for driving the printing drum has been found to be impractical for well founded 35 reasons. As will be understood by those acquainted with the operation of a multigraph apparatus the type banks are formed in a segment drum which is mounted, when in use, on the main printing drum. The segment drum when mounted on the main printing drum has the effect of a counter weight or balance, that is to say, that when the printing drum is rotated the segment drum during its downward rotation, causes the 40 momentum of the printing drum to increase to a speed greater than the rotation of the platen gear. As all gears are designed so as to permit a slight play between the engaging teeth the increase momentum of the printing drum causes the printing drum gear to suddenly take up this play. As the paper 45

passes between the platen roller and the type, set in the type banks formed in the segment drum the sudden increase in the momentum of the printing drum causes the type to rub on the surface of the paper producing a blurry effect. This effect would even be greater when the gear teeth become more and more worn. Such existing conditions have cost manufacturers and mail order houses, who make a practice of mailing form letters printed by a multigraph apparatus to their customers, a large amount of money through waste and excess labor. As will be observed by the following description of my improved driving means, I have completely overcome the conditions as herein mentioned.

In carrying my invention into effect and with reference to the accompanying drawings, 5 indicates a multigraph apparatus of any improved type, 6 the base and 7 the stand. Revolubly mounted on the ends of the multigraph apparatus is the usual printing drum 8 having gear teeth 9 formed around its periphery adjacent one end thereof. The multigraph apparatus 5 is also provided with the usual form of type carrying segment drum 10 and a platen roller 11 which engages the type carrying segment 80 drum 10 when in operation. Mounted on the platen roller shaft 12 is a gear 13, of the usual form, which meshes with the printing drum gear teeth 9 and which through the medium of an idle gear 14 drives the feed 85 roller gear 15. This description, so far, involves parts which are known to be used in connection with any improved type of multigraph apparatus but which are necessary to set forth in order to more fully describe my 90 improved driving means.

Mounted on the edges of each of the ends of the multigraph apparatus 5 are bearings 16 and 17 which are preferably formed integrally with the said ends. A shaft 18 is 100 journalled in the bearings 17 and 18, and projects beyond one of the ends of the multigraph apparatus, as at 19, (Fig. 1). Rigidly mounted on the projecting end of the shaft, by any suitable manner, is a grooved 105 cone pulley 20 which is operatively connected to an electric motor (not shown) by a suitable belt 21. Mounted on the opposite end of the shaft 18 adjacent the inner face of the bearing 17 is a suitable driving gear 110 22 which meshes directly with the gear teeth 9 formed on the periphery of the printing

drum 5. The driving gear 22 is shiftably mounted on the shaft 18 and keyed thereto by means of the key 23'. The shifting of the gear 22 is accomplished through the medium of a spring held shaft 24' which is slidably mounted on a lug 25' formed integrally with the bearing 17.

Integrally formed on the inner end of the shaft 24' is a depending arm 26' which is provided with a ring member 27' engaging a recess 28' formed in the hub 22' of the gear 22. This arrangement is such that when desired, the gear 22 may be shifted on the shaft 18 in order to mesh with a signature attachment (not shown) which is frequently used in connection with a multigraph apparatus. By this arrangement of driving means it will be noted that by meshing the driving gear 22 directly with the printing drum gear teeth 9, instead of through the medium of a platen roller gear, herein mentioned, the momentum of the printing drum 5 is the same at all times. Thus, by this arrangement, the printing types carried by the segment drum 25 are prevented from rubbing on the paper which would produce a blurry effect. It will also be noted that printing drum gear teeth drive the platen roller 11 which in turn drives the feed roller gear 15 through the medium of the idle gear 14. By this arrangement it will also be noted that the speeds of all the revolving parts will be timed according to their individual functions and this condition will always be the same even when the engaging teeth begin to wear. By my improved driving means a high quality of work can be produced at a very low cost. In connection with my improved means for driving the printing drum 5, I provide means for operating an automatic paper feed roller, of the usual construction used in connection with multigraph apparatus, and which, by my construction, is driven directly by the printing drum roller. This means comprises a rocker shaft 24 journalled on suitable bearings 25 formed integrally on the ends of the multigraph apparatus 5. Rigidly mounted on one end of the rocker shaft 24 is an oscillating arm 26 which is pivotally connected to a tooth rack bar 27 meshing with a pinion 28 mounted on the shaft 29 of an automatic feed roller 30 which automatically feeds paper to the platen roller 11. Mounted on the opposite end of the rocker shaft 24 is a rocker arm 31 which is pivotally connected to a bell crank 32 through the medium of a connecting link 33. This construction is such that upon every revolution of the printing drum 5 the rocker shaft 24 is caused to rock through the medium of the rocker arm 31, and the bell crank 32, oscillating the rack bar 27 through the medium of the oscillating arm 26 which rotates the automatic feed roller 29.

It will be seen that by my improved means

for driving the printing drum of a multigraph apparatus, the driving power is applied directly to the printing drum preventing any possibility of the printing types blurring the print which might be caused by the increase momentum of the printing drum through the medium of the segment drum which has the effect of a counter balance or weight.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. In a driving means for a multigraph apparatus, the combination with a revoluble printing drum, of a transversely disposed power driven shaft mounted on said apparatus; and driving means mounted for longitudinal movement with respect to the shaft and adapted to be directly applied to said drum, substantially as described.

2. In a driving means for a multigraph apparatus, the combination with a revoluble printing drum having gear teeth formed on the periphery thereof, of a power driven gear adapted to be shifted into meshed relation with respect to said teeth for applying driving power directly to said drum, substantially as described.

3. In a driving means for a multigraph apparatus, the combination with a revoluble printing drum having gear teeth formed on the periphery thereof, of a transversely disposed driving shaft mounted on the opposite ends of said apparatus and provided with shiftable means for transmitting driving energy directly to said drum, substantially as described.

4. In a driving means for a multigraph apparatus, the combination with a revoluble printing drum, of gear teeth formed on the periphery of said drum adjacent the end thereof; a transversely extending shaft mounted on said apparatus; a shiftable pinion mounted on said shaft meshing directly with said gear teeth for applying driving energy directly to said drum means for shifting said pinion; and a cone pulley mounted on the opposite end of said shaft, substantially as described.

5. In a driving means for a multigraph apparatus, the combination with a revoluble printing drum, of teeth formed on the periphery of said drum adjacent one end thereof; bearings formed on the opposite ends of said drum; a transversely disposed

shaft journalled on said bearings; a shiftable pinion on one end of said shaft meshing with said gear teeth for applying driving power directly to said drum; and driving means 5 mounted on the opposite end of said shaft, substantially as described.

6. In a driving means for a multigraph apparatus, the combination with a revoluble drum having gear teeth formed on the periphery thereof and an automatic feed roller therefor, of a transversely disposed shaft mounted on the opposite ends of said apparatus; a gear on said shaft meshing with

said gear teeth for applying driving power directly to said drum; and a transversely disposed rocker shaft mounted on said apparatus and operatively connected to said roller and said drum, substantially as described.

In testimony whereof I have signed my name to this specification in the presence of two subscribing witnesses.

WALTER E. VERKLER.
